SIGN

Arthur C. Fisher, North St. Paul, Minn.

Application February 1, 1932, Serial No. 589,993

4 Claims. (Cl. 40—130)

My invention relates to signs and particularly to signs used for advertising and has for its object to provide a sign of a highly spectacular nature.

5 An object of the invention resides in providing a sign having a pyrotechnic advertising display.

A still further object of the invention resides in providing a sign having a frame with a support thereon and having lances mounted on the support at spaced intervals and conforming to the configuration of the display.

Another object of the invention resides in providing igniting means for igniting all of the 15 lances.

A feature of the invention resides in constructing the support elongated in form and flexible to conform to the configuration of the display.

20 An object of the invention resides in arranging the lances in groups and in providing separate quick matches for igniting the lances in each group and in providing a slow match between the first named matches for procuring 25 delayed ignition of one of the groups of lances.

Other objects of the invention reside in the details of construction thereof, and in the novel combination and arrangement of parts herein- 30 after illustrated or described.

30 In the drawings:

Fig. 1 is a perspective view of a sign illustrating an embodiment of my invention.

Fig. 2 is an elevational view of the sign in action.

35 Fig. 3 is a detail view illustrating the manner of attaching the lances to the supports.

In the presentation of advertising matter to the public a much greater impression is made where the display is highly spectacular. The 40 present invention utilizes this principle by providing a display in which pyrotechnics are employed.

My invention comprises a sign which I have indicated in its entirety at A in Figs. 1 and 2.

45 This sign is constructed with a frame B consisting of two uprights 10 and 11 which are connected together at their upper and lower ends through rails 12 and 13. All of these members may be made more or less ornamental and 50 if desired ornamental caps 14 may be applied to the upper ends of the uprights 10 and 11.

Within the frame B is disposed a supporting structure C which consists of a number of equally spaced horizontal lattice bars 15 which are 55 connected to and carried by the uprights 10

and 11. Extending across these bars are other vertical lattice bars 16 which are secured to the rails 12 and 13 of frame B and which are also attached to the lattice bars 15. By means of this construction a rigid and light supporting structure is provided on which the display can be built and which will permit of the attachment of the support proper at suitable intervals throughout its extent. In addition the supporting structure is adaptable without alteration to any desired arrangement of supports which may be desired in the formation of the display.

The display proper is shown in action in Fig. 2 and consists of groups of burning masses arranged to outline letters or any desired embellishments to be incorporated in the particular design depicted. In the drawings the entire display is designated by the reference character D and the various letters forming the constituent parts thereof by reference numerals 17, 18, 19, 20, 21, 22 and 23. These letters are arranged to describe the goods to be advertised, the trade-mark, manufacturer or whatever other data is desired to be conveyed to the public. The means for procuring these letters being identical, only that used in forming letter 17 will be described in detail.

In the construction of the display a piece of rattan, or a soft pliable willow twig 24 is employed which is arranged upon the supporting structure C at the proper locality and bent to simulate the letter "J". This piece of rattan forms a support and is nailed down to the supporting structure C wherever said support crosses either the horizontal lattice members 15 or the vertical lattice members 16 of said supporting structure. In like manner similar pieces of rattan are laid out and nailed to the supporting structure to conform to the other letters 18 to 23, said supports being arranged in proper position on the supporting structure to correspond with the outline of the composite display. In the application of these supports to the supporting structure the pieces of rattan may be continuous for several letters, run beyond the confines of the letters where desirable to permit of attachment to adjacent lattice bars and may cross each other or be otherwise arranged as found most expedient in the application of the same to the sign.

At suitable intervals along the support 24 are attached to it a number of lances 25 which may be secured thereto in any of a number of different ways. These lances are constructed in

accordance with the usual practice in pyrotechnics and are each provided with a tubular case 26 filled with a core 27 of a suitable combustible having in it a chemical adapted to color the 5 flame produced in the combustion thereof. The simplest manner of attaching these lances to the support 24 consists in utilizing double pointed tacks 28 which extend into one end of the lance and are driven into the rattan strip constituting 10 the supporting member. By means of these tacks the various lances may be mounted in proper position so that when the same are subsequently ignited the desired outline is portrayed in flame. It can readily be comprehended that 15 clips or other similar attaching members may be employed for securing the lances to these supports. Such construction being well known in the art has, however, not been disclosed in this application. In like manner, lances are attached 20 to all of the other supports of the entire sign and confined to the particular portions thereof conforming to the letters or to the embellishments to be depicted.

For the purpose of igniting the various lances 25 ordinary matches such as employed in pyrotechnics may be utilized. These matches consist of a wick or cord chemically prepared to burn at a uniform rate and are preferably encased in a suitable paper case which increases the rate 30 of propagation of the flame, causing the said match to burn almost instantaneously. In the particular sign employed, two matches indicated at 29 and 30 are employed, the match 29 serving to ignite the lances used in the word "J. Doe" 35 and the match 30 operating to ignite the lance used in the word "Gum". The match 29 is shown in detail in Fig. 3 and its manner of attachment to the lances is also illustrated. In this figure the treated cord or wick is indicated at 31, and the paper case enclosing the same at 32. The match is attached to the ends of the various lances through short pins or nails 33 which extend through the paper case 32 and into the core 27 of the various lances. The 40 match 29 commences with the letter J, the free end thereof being indicated at 34 and passes successively about the various lances 25, being attached thereto as described. The match 29 then continues over the upper part of the D and 45 passes around the curved portion thereof, loops to catch the period, comes back over the vertical part of the letter D, loops about the letter O and catches the vertical part of the letter E and the lower bar thereof. A branch match 35 is spliced 50 to the match 29 and catches the other bars of the letter E. The match 30 in like manner is attached to the various lances of the word "Gum" and passes successively along the letters G and U and takes in the two vertical parts and 55 one of the inclined parts of the letter M. A branch match 36 similar to the match 35 takes in the other bar of this letter. The two matches 29 and 30 are preferably of the rapid burning type such as known as quick matches and operate almost instantaneously to ignite the various lances connected to the same. This is accomplished through the holes formed in the paper case 32 by means of the pins or nails 33. When the flame reaches these localities of the 60 case the flame blows through the holes formed by said nails and ignites the core 27 of the various lances which is exposed at the outer end thereof.

If desired, the two matches 29 and 30 may be 70 directly connected together so as to cause the

entire sign to be instantaneously brought into action. However, delayed action of one or the other of the words may be had by inserting a slow burning match 37 between the two matches 29 and 30. Such matches may be readily procured by utilizing the chemically treated wick without a case, which causes the same to burn more slowly and produce a certain lapse of time between the firing of the two sections of the sign controlled through the matches 29 and 30. If it be desired that the word "J. Doe" be first fired, match 29 is lighted through the free end 80 34 thereof which causes a rapid ignition of the lances used in the formation of the word "J. Doe". As soon as the slow burning match 37 85 is reached, lances forming the word "Gum" are ignited which occurs at a time interval subsequent to that at which the lances of the word "J. Doe" were ignited. The various lances then 90 continue to burn until all of the combustible material therein has been burned up.

In the construction of advertising signs in accordance with my invention any type of wording may be employed and the invention may be 100 used to show trade-marks, the names of manufacturing concerns, articles to be advertised as well as slogans used in conjunction therewith. In addition, embellishments may be employed in conjunction with the word parts of the sign to 105 give the same any desired appearance. Lances giving various colors of flame may also be employed so that a highly spectacular and attractive display may be had. If desired different lengths of lances may be used so that certain 110 of the portions of the display continue burning longer than other portions of the display.

In the use of my invention the particular design is laid out on the frame C as explained, using a strip of rattan or other suitable material. The lances are then applied to the same and the matches lastly attached thereto. This is done any time in advance of the firing of the display which, of course, is preferably exhibited after dark. At the proper moment the desired match is ignited which causes the ignition 115 of the various lances and the subsequent bursting of the entire sign into flame to give the desired visual and spectacular effects.

During day time the frame B forms an attractive enclosure for the supporting structure and the other parts carried thereby. During firing the said frame becomes illuminated through the flames from the various lances which adds to the attractive appearance of the 120 display and enhances the beauty of the same. This framework at the same time forms a support for the bars which are preferably constructed relatively light thereby permitting of the erection of fairly large signs with extreme 125 ease and simplicity.

In the construction of my invention it can readily be comprehended that any suitable material may be used for the supports and that the lances may be attached to the same through 130 any suitable clips or fastening means. Likewise any type of supporting structure may be employed and the supporting structure built in sections on the ground and subsequently erected on the framework B after the formation of the 135 same. Likewise the framework B may be constructed in parts and assembled in position at the site so that the entire sign may be easily transported to the locality of the erection.

My invention is highly advantageous in that 140

- an extremely spectacular and effective sign is produced whereby advertising matter may be readily impressed upon the minds of the observers. Any desired advertising data may be exhibited so that an endless variety of different signs may be readily had without appreciable change in construction and utilizing the same supporting structure. The sign may be used repeatedly for similar or different signs and may 10 be constructed at an economical cost. Changes in the specific form of my invention, as herein disclosed, may be made within the scope of what is claimed without departing from the spirit of my invention.
- 15 Having described my invention, what I claim as new and desire to protect by Letters Patent is:
1. A sign for exhibiting an advertising display comprising a supporting structure, a support thereon conforming to the configuration of the display, a plurality of lances carried by the support and following along the same, and means for igniting all of said lances.
  2. A sign for exhibiting an advertising display comprising uprights, a frame extending between said uprights, elongated flexible supports carried by the frame and arranged to conform to the configuration of the display, a plu-
- rality of lances attached to said supports in spaced relation to one another and following along the same and a match connected to all of said lances.
3. A sign for exhibiting an advertising display comprising a supporting structure, a support thereon conforming to the configuration of the display, a plurality of lances carried by the support and following along the same, said lances being arranged in groups, means for igniting the lances of one of said groups, means for igniting the lances of another of said groups and timed means for propagating combustion between said igniting means to cause subsequent ignition of one of the groups of lances.
4. A sign for exhibiting an advertising display comprising a supporting structure, a support thereon conforming to the configuration of the display, a plurality of lances carried by the support and following along the same, said lances being arranged in groups, a quick match for igniting the lances of one of said groups, a quick match for lighting the lances of another of said groups and a slow match connecting the two quick matches.
